UNITED STATES PATENT OFFICE.

JAMES A. DU LANEY, OF SEATTLE, WASHINGTON, ASSIGNOR OF ONE-HALF TO CHARLES R. NELSON, OF SEATTLE, WASHINGTON.

ELECTRIC-HEATED CLOTHES-PRESSER.

1,272,638.

Specification of Letters Patent. Patented July 16, 1918.

Application filed November 28, 1917. Serial No. 204,309.

To all whom it may concern:

Be it known that I, JAMES A. DU LANEY, a citizen of the United States, and resident of the city of Seattle, county of King, and 5 State of Washington, have invented certain new and useful Improvements in Electric-Heated Clothes-Pressers, of which the following is a specification.

My invention relates to clothes pressing 10 machines and consists of an apparatus for pressing clothes wherein electricity is employed for superheating the steam and comprises the novel parts and combinations of parts which will be hereinafter described 15 and then particularly pointed out in the claim.

The object of my invention is to provide an effective device in which electric heat may be employed to insure the delivery of 20 dry steam upon the article being pressed.

In the accompanying drawings I have shown my invention in the type of construction which is now most preferred by me.

Figure 1 is a top plan view of the ma- 25 chine.

Fig. 2 is a front elevation.

Fig. 3 is an end elevation.

Fig. 4 is a longitudinal section through the upper presser plate.

30 Fig. 5 is a transverse section through the presser.

Fig. 6 is a top plan view of a modified lever system for handling the swinging presser.

35 Fig. 7 is a side view of this modified lever system.

The pressing apparatus consists of a lower presser plate or "buck", 1, and a comple- 40 mental upper plate 10 which is mounted upon levers 2 which are pivoted at 20 upon a member of the frame 3.

The frame has a top 30 upon which to support the clothing being pressed. Sup- 45 ported above this is the lower presser plate or buck 1.

In the lower part of the frame is placed a small boiler 4. This may be heated by any suitable and convenient means. I have shown electric leads 40 and contemplate em- 50 ploying electric heating mechanism, which may be of any suitable type.

A pipe 41 leads from this boiler to the lower presser plate or buck and a pipe 42 connects the boiler with a bore in one end

of the shaft 21. This bore is connected by 55 the pipe 43 with the upper presser plate 10. The connection of pipe 42 with the shaft 21 is such as to permit such turning movement as occurs when the top plate is raised or lowered.

60 In the type of operating mechanism shown in Figs. 1, 2 and 3, an arm 22 extends beyond their pivot point 20 and is connected by a link 23 with the arm 24 of a lever which has arms 25 and 26 and is pivoted at 27. The arm 25 has a counterweight 28 thereon, to return the parts to the position where the top presser plate 10 is raised.

65 The arm 26 is connected by a link 35 with a treadle lever 37 which is pivoted at 38 to 70 the frame. A downward movement of the treadle lever raises the counterweight 28 and brings down the upper presser plate 10.

75 In the modified construction shown in Figs. 6 and 7, the torsion springs 15 upon pivot shaft 21, is substituted for the counterweight and a crank arm 29 upon the shaft 21 is connected by a link 35 with the treadle lever 37.

80 The interior construction of the pressing plates is shown in Figs. 4 and 5. A description of the upper one 10 will suffice for both.

85 The main body of this consists of a casting 5 which has a chamber 50 constituting a steam distributing chamber. The press- 85 ing face of this part has a large number of small holes 51, through which the steam is discharged into the presser cloth.

90 The opposite face of the casting 5 has a hole 52 through which the steam distrib- 90 uting pipe 44 is passed. This latter pipe is perforated to discharge steam throughout its length. The part 5 is preferably made of aluminum. The hole 52 in its top wall is preferably closed by an inserted plate 53. 95

95 Above the base 5 is a plate 6, of a heat- 100 resistant and electrically non-conductive material, as one composed of asbestos. To the surface of this are secured coils 60 of a resistance metal which constitute the heat- 100 ing element. Outside of this is a mass 63 of insulating material held in place by a metal cap 64. Feed wires or leads 61, 62 enable the heating elements to be connected with suitable feed wires.

105 I preferably cover the pressing faces of the pressers with a layer 7 of porous material as asbestos, and this with a cloth 8

and have the edges of both extend over the bottom edges of the plate and turn up, and secure both by an encircling band 70.

What I claim as my invention is:

- 5 In a clothes presser, a hollow head having a steam chamber provided with a perforated pressing face, a perforated steam distributing pipe extending lengthwise said steam chamber, a cap constituting a cover fitting 10 the back side of the head, the head having

a marginal flange at its back, a heating element, a plate to which the heating element is secured, said plate being held between said marginal flange of the head and the cover with the heating element toward the steam chamber, and insulating material between said plate and the body of the cover. 15

Signed at Seattle, Washington, this 19th day of November, 1917.

JAMES A. DU LANEY.
